HYDROCRACKING PROCESS STARTUP

John H. Duir, Fullerton, and Arnold E. Kelley, Orange, Calif., assignors to Union Oil Company of California, Los Angeles, Calif., a corporation of California
Filed Apr. 6, 1964, Ser. No. 357,445
9 Claims. (Cl. 208—89)

This invention relates to the catalytic hydrocracking of high-boiling hydrocarbon feedstocks to produce therefrom lower boiling hydrocarbons, and more particularly is concerned with methods for initiating such hydrocracking processes starting with a fresh, or freshly regenerated, catalyst. More specifically, the invention is concerned with the "integral" hydrofining-hydrocracking train, wherein a nitrogen-containing feedstock is first subjected to catalytic hydrofining to decompose organic nitrogen compounds, and total effluent therefrom is then subjected to catalytic hydrocracking (in the presence of the ammonia formed during the hydrofining operation). The basic object of the invention is to bring the hydrocracking catalyst onstream at operative conversion temperatures while avoiding any initial poisoning of the catalyst resulting from contact with the organic nitrogen compounds in the feed, and at the same time avoiding any "shock" damage to the catalyst resulting from an initial high-temperature contacting of hydrocarbon feeds therewith.

In broad aspect, the startup procedure consists in gradually heating both the hydrofining and hydrocracking catalyst beds up to the desired reaction temperatures by circulating through both beds in series a preheated mixture of hydrogen and a startup feedstock which is substantially free of organic nitrogen, while adding ammonia to said feedstock in such manner so as to exert a temporary poisoning effect upon the hydrocracking catalyst. Upon reaching operative hydrofining and hydrocracking temperatures, the desired nitrogen-containing process feedstock is substituted for the startup feed. By operating in this manner, both the hydrofining zone and the hydrocracking zone can be maintained onstream in series throughout the startup procedure, and due to the safety factor of the added ammonia, little or no temperature control is required of the hydrofiner effluent which goes to the hydrocracker. Such a system is well adapted for use in a single integrated unit wherein both the hydrofining catalyst and the hydrocracking catalyst are located in the same reactor.

In the catalytic conversion of hydrocarbons, the initial contacting of the feedstock with the fresh, or freshly regenerated, catalyst can have a profound effect upon the subsequent activity of the catalyst throughout the run. If adequate precautions are not exercised during the first few hours or even minutes of contacting, an entire batch of catalyst may be ruined, or explosive runaway reactions may be initiated which are substantially uncontrollable. The fresh, or "wild," activity of the catalyst must be gradually tempered to the feedstock and process conditions in such manner as to avoid runaway reactions and/or unduly rapid coking rates. At the same time, precautions must be taken to avoid poisoning by impurities which may be present in the feedstock. These problems are particularly aggravated in the case of the integral hydrofining-hydrocracking contacting train wherein the feedstock contains organic nitrogen compounds. The basic problem involves how to get the hydrofining catalyst heated to the operative hydrofining temperatures (so that substantially all of the organic nitrogen compounds will be decomposed to ammonia) before the hydrofiner effluent contacts the hydrocracking catalyst. It has been found that ammonia exerts a readily reversible poisoning effect upon the hydrocracking catalyst, whereas

2

the organic nitrogen compounds in the feed bring about a relatively permanent deactivation which is reversible only by oxidative regeneration, or by very high temperature stripping.

One obvious answer to the above problem would appear to reside in simply heating the hydrofining catalyst bed and the hydrocracking catalyst bed separately, in parallel. This solution is not feasible in cases where both catalysts are enclosed in the same reactor, and moreover is undesirable even when the catalysts are enclosed in separate reactors because of the added equipment required, and the unreliability of certain of the necessary valving arrangements in hot feed lines.

A second apparently feasible solution would be simply to circulate heated hydrogen, or an inert gas, serially through the hydrofining catalyst and then through the hydrocracking catalyst until both beds are heated to the desired reaction temperature, after which the flow of hydrocarbon feed is started. This is not practical however because it is undesirable to contact hydrocarbon feedstock initially with the catalyst at the desired conversion temperature. It is much safer, and less damaging to the catalyst, if the feedstock contacts the catalyst first at relatively low temperatures, considerably below the ultimately desired conversion temperature, in order to precondition the catalyst and temper its initial high activity.

In a copending application, Serial No. 265,648, filed March 18, 1963, now U.S. Patent No. 3,186,936, it has been proposed to solve these problems by circulating a preheated nitrogen-free startup feedstock in series through the hydrofiner and the hydrocracker until the hydrofining catalyst is heated to the desired conversion temperature of, e.g., 700° F., and during this heatup period, avoiding a runaway reaction in the hydrocracking catalyst bed by cooling the hydrofiner effluent to around 400° F. before it enters the hydrocracker. (It is imperative to avoid any contact of nitrogen-free feed mixtures with the fresh hydrocracking catalyst at temperatures above about 400–450° F.; otherwise a runaway exothermic reaction may result.) After the hydrofining catalyst reaches the desired conversion temperature, the nitrogen-containing process feed is then substituted for the startup feed, and after this point the hydrocracking catalyst bed can be raised to reaction temperature safely and gradually by means of the ammonia-containing hydrofiner effluent. This procedure is feasible, but is disadvantageous from a safety standpoint in that, during the initial heatup with nitrogen-free feedstock, a failure in the interstage hydrofiner effluent cooling facilities, e.g., a power failure, could result in a runaway reaction in the hydrocracker before the system could be depressured or otherwise brought under control. The process of this invention avoids this danger, as well as the other difficulties above discussed.

In addition to its operational advantages over the process described in Serial No. 265,648, the startup procedure of this invention is also found to yield in most cases a catalyst of higher initial activity than the process of Serial No. 265,648. This is presumably due to the more complete protection against organic nitrogen compounds which is afforded by the present process, but may also be due to in some measure to a specific desirable effect of ammonia on the hydrocracking catalyst at low temperatures.

The poisoning effect of organic nitrogen compounds upon hydrocracking catalyst is well-recognized in the art. It is known that the effect can be minimized by operating at relatively high hydrocracking temperatures, which favor desorption of nitrogen compounds. However this solution to the problem is not practical because high hydrocracking temperatures give relatively nonselective cracking, with much production of light gases and coke. We

have found however that at relatively low hydrocracking temperatures, below about 825° F., there is a marked difference between the poisoning effect of organic nitrogen compounds (or at least some types thereof), as compared to ammonia. With a sufficiently active catalyst, substantial amounts of ammonia can be tolerated in the reaction zone, whereas organic nitrogen compounds are much more detrimental. Specifically, it has been found that organic nitrogen compounds tend to become irreversibly adsorbed on the catalyst, and exert a relatively permanent poisoning effect at the low hydrocracking temperatures employed herein. As a result of this phenomenon, if the hydrocracking catalyst is brought up to hydrocracking temperatures, as, e.g., from room temperature, by means of preheated feed-hydrogen mixtures containing organic nitrogen compounds, a much lower activity is obtained than if the feed were pretreated to decompose the organic nitrogen compounds into ammonia. Moreover, this low activity level persists for at least several weeks, and normally cannot be reversed except by going to hydrocracking temperatures above about 825° F., at which the catalyst is damaged by coke laydown.

From the foregoing, it will be apparent that the principal objective of the invention is to provide economical methods for the hydrocracking of nitrogen-containing feedstocks at relatively low temperatures, below about 800° F. A further object is to provide methods for hydrocracking nitrogen-containing feedstocks which avoid the conventional and expensive non-integral prehydrofining of such feedstocks with its concomitant interstage condensation and washing to remove ammonia therefrom. A specific objective is to provide, in an integral hydrofining-hydrocracking sequence, a convenient and economical method for raising the hydrofining and hydrocracking catalyst to the desired operating temperatures without damaging the hydrocracking catalysts. Other objectives will be apparent from the more detailed description which follows.

Reference is now made to the accompanying drawings wherein FIGURE 1 is a flowsheet illustrating a preferred startup procedure of the invention, and FIGURE 2 is a graph depicting a specific illustrative startup schedule (carried out at 1,500 p.s.i.g., a feed rate of 1.0 LHSV in the hydrofiner, and 1.5 LHSV in the hydrocracker) wherein feed composition, ammonia addition, and reactor inlet temperatures are correlated with time. The flow diagram of FIGURE 1 will be explained with specific reference to the startup schedule of FIGURE 2.

In FIGURE 1, hydrofiner 2 is operated adiabatically, but if desired, a more isothermal operation may be obtained by means of one or more intermediate quench points, as in hydrocracker 4. Hydrocracker 4 is semi-adiabatic in that two hydrogen quench points are utilized between hydrocracking catalyst beds 6, 8 and 10. At the beginning of the operation to be described, hydrofining catalyst bed 12 and hydrocracking catalyst beds 6, 8 and 10 have been freshly activated and brought to a temperature of about 300° F. by means of a circulating recycle hydrogen stream. The hydrofining catalyst is also preferably in a presulfided condition.

The process utilizes a low-nitrogen startup feed, and a high-nitrogen process feed. The startup feed should contain less than about 100 parts, and preferably less than about 10 parts per million of organic nitrogen; the process feed contains relatively more nitrogen, up to about 2% by weight or more. Either or both of the feedstocks may contain sulfur in amounts up to about 5% by weight, although it is preferable to use a startup feed which contains less than about 1% of sulfur. In other respects the feeds may if desired be similar in character, although it is further preferred that the startup feed contain less than about 35% by volume of aromatic hydrocarbons in order to minimize exothermic temperature rises in hydrocracker

4. Preferred characteristics of the respective feedstocks are as follows:

TABLE 1

	Startup Feed	Process Feed
Boiling range, ° F.:		
Initial boiling point.....	350-600	400-550
End-boiling-point.....	450-650	500-1,000
Gravity, ° API.....	25-40	15-35
Nitrogen, p.p.m.....	0-50	50-20,000
Sulfur, wt. percent.....	0-1	0-5
Aromatics, vol. percent.....	0-35	10-60

To initiate the startup procedure, valve 14 in low-nitrogen startup feed line 16 is opened, as well as valve 18 in ammonia injection line 20, while valve 22 in high-nitrogen feed line 24 is closed. The startup feed plus ammonia (preferably anhydrous liquid ammonia) thus flows from lines 16 and 20 respectively into reactor feed line 26 wherein it is mixed with hydrogen from line 28. The hydrogen used during the startup sequence is preferably sour, containing, e.g., from 0.1-1% by volume of hydrogen sulfide, in order to maintain the hydrofining catalyst in a sulfided condition, and to effect a gradual sulfiding of the hydrocracking catalyst. The ratio of hydrogen to feed in line 26 is preferably between about 1,000 and 20,000 s.c.f./b. The startup feed flow rates may be substantially in the range of the flow rates hereinafter specified for the high-nitrogen process feeds, and the respective pressures may also be in the same range. Preferred ammonia concentrations during startup range between about 0.1 and 1% by weight of the startup feed. The ammonia may be added in the form of gaseous or anhydrous liquid ammonia, or in the form of easily decomposable organic nitrogen bases such as aliphatic amines, e.g., butyl amine, isopropyl amine, etc. Further, it may be added either to the hydrofiner feed as illustrated, or it may be added to the hydrofiner effluent in line 31.

In preheaters 30 and 32, the inlet temperature of the respective feed mixtures is raised gradually, e.g., about 10 to 50° F. per hour, starting at about 300° F. This operation is preferably continued until bed temperatures in hydrofiner 2 and hydrocracker 6 reach levels somewhere in the range of about 400-500° F. Before this point is reached however, it will normally be found that the wash water withdrawn via line 34 from high-pressure separator 36 will contain substantial amounts of ammonia, indicating that both the hydrofining catalyst and the hydrocracking catalyst have become substantially saturated with adsorbed ammonia. Care should be taken not to allow the hydrocracking catalyst temperature to rise above about 500° F. until there has been a substantial breakthrough of ammonia as indicated by its appearance in the wash water from line 34.

In the schedule illustrated in FIGURE 2, an inlet temperature of about 450° F. is reached in each reactor after about 6 hours, as indicated on temperature curve A. At this point, substantial amounts of ammonia begin to appear in the wash water from line 34, and hence the amount of ammonia injected via line 20 is reduced from the original 0.5% by weight to about 0.2%, as indicated by ammonia injection profile line B. After reducing the ammonia concentration it may be desirable to operate for a short period without further temperature rise in order to be sure that the lower ammonia concentration does not bring about undesirable exothermic temperature rises in reactor 6. During the entire startup procedure, it is preferable that none of the catalyst bed temperatures in reactor 6 be allowed to rise more than about 30° F. above the reactor inlet temperature. This may be controlled to some extent by means of cool quench hydrogen injected via lines 38 and 40.

Ammonia injection at the lower level of about 0.2% is then continued, while again raising the reactor inlet temperatures about 10-50° F. per hour, until the desired ini-

tial hydrocracking and hydrofining temperatures, e.g., about 600-700° F., are reached. At this point, the flow of high-nitrogen process feed may be initiated by opening valve 22 in line 24. Ammonia injection is preferably continued for a short time after the start of the high-nitrogen process feed, but may if desired be terminated substantially simultaneously with the use of high-nitrogen feed. It is entirely feasible to terminate completely the use of the low-nitrogen startup feed as soon as operative catalyst bed temperatures have been reached. However, in the modification illustrated in FIGURE 2, the termination of startup feed and the substitution of process feed proceeds stepwise over a period of several hours in order to avoid any unexpected upset in process conditions, and provide a smoother transition from 100% startup feed to 100% process feed. Thus, over four-hour intervals, the startup feed is reduced from 100% to 70%, to 50%, to 0, while process feed is increased from 0 to 30%, to 50%, to 75%, to 100%, as illustrated by lines C and D respectively. Ammonia injection is terminated about 4 hours after the shift to 30% process feed.

It will be understood that during the startup cycle, the effluent from hydrocracker 4 is withdrawn via line 42, condensed in condenser 44, and transferred via line 46 to high-pressure separator 36. Wash water is injected into line 46 via line 48. The hydrogen recovered in high-pressure separator 36 is then recycled to the process via line 28, with makeup hydrogen and hydrogen sulfide being added via line 50. The high-pressure condensate in separator 36 is flashed via line 52 into low-pressure separator 54, from which light hydrocarbon gases are exhausted via line 56. Low-pressure condensate in separator 54 is then transferred via line 58 to fractionating column 60, for the recovery of butanes via overhead line 62, gasoline-boiling-range material from sidecut line 64, and gas oil as bottoms via line 66. During the startup cycle, the gas oil in line 66 may be recycled directly to line 26, or in another modification, the entire low-pressure condensate in separator 54 may be recycled back to the hydrofiner, thus bypassing fractionating column 60. Ordinarily, however it is preferred to fractionate the startup effluent to recover any gasoline synthesized in hydrocracker 4.

With hydrofiner 2 and hydrocracker 4 now on-stream with high-nitrogen process feed, operative process conditions fall within the following general ranges:

TABLE 2

	Hydrofining Conditions	
	Operative	Preferred
Temperature, ° F. (av. bed):		
Beginning of run.....	650-750	680-725
End of run.....	700-850	750-800

H ₂ /oil ratio, M.s.c.f./b.....		

The same general conditions may be observed during the pretreatment sequence, except for temperatures which are adjusted as previously described.

Suitable hydrofining catalysts for the prehydrofining operation include in general the oxides and/or sulfides of the Groups VIB and/or Group VIII metals, preferably supported on a relatively noncracking adsorbent oxide carrier such as alumina, silica, titania, and the like. Preferred hydrofining catalysts include for example mixtures of the oxides and/or sulfides of cobalt plus molybdenum,

nickel plus molybdenum, or nickel plus tungsten, preferably supported on a carrier such as alumina, or alumina containing a small amount of coprecipitated silica gel.

The hydrocracking catalysts employed herein may consist of any desired combination of a refractory cracking base with a suitable hydrogenating component. Suitable cracking bases include for example mixtures of two or more difficultly reducible oxides such as silica-alumina, silica-magnesia, silica-zirconia, alumina-boria, silica-titania, silica-zirconia-titania, acid-treated clays and the like. Acidic metal phosphates such as aluminum phosphate may also be used. The preferred cracking bases comprise partially dehydrated, zeolitic, crystalline molecular sieves, e.g., of the X or Y crystal types, having relatively uniform pore diameters of about 8-14 Å., and comprising silica, alumina and one or more exchangeable zeolitic cations.

A particularly active and useful class of molecular sieve cracking bases are those having a relatively high SiO₂/Al₂O₃ ratio, e.g., between about 3.0 and 10. The most active forms are those wherein the exchangeable zeolitic cations are hydrogen and/or a divalent metal such as magnesium, calcium or zinc. In particular, the Y molecular sieves, having crystal pores of about 9-10 Å. in diameter, and wherein the SiO₂/Al₂O₃ ratio is about 4-6 are preferred, either in their hydrogen form, a divalent metal form, or a mixed divalent metal-hydrogen form. Normally, such molecular sieves are prepared first in the sodium form, and the sodium is ion-exchanged out with a divalent metal, or where the hydrogen form is desired, with an ammonium salt followed by heating to decompose the zeolitic ammonium ion and leave a hydrogen ion. (These hydrogen zeolites are sometimes referred to as being "decationized.") Molecular sieves of this nature are described more particularly in Belgian Patents Nos. 577,642, 598,582, 598,683 and 598,682.

The foregoing cracking bases are compounded, as by impregnation, with from about 0.5% to 25% (based on free metal) of a Group VIB and/or Group VIII metal promoter, e.g., an oxide or sulfide of chromium, tungsten, cobalt, nickel, or the corresponding free metals, or any combination thereof. Alternatively, even smaller proportions, between about 0.05% and 2% of the metals platinum, palladium, rhodium or iridium may be employed. The oxides and sulfides of other transitional metals may also be used, but to less advantage than the foregoing.

In the case of zeolitic type cracking bases, it is desirable to deposit the hydrogenating metal thereon by ion exchange. This can be accomplished by digesting the zeolite with an aqueous solution of a suitable compound of the desired metal, wherein the metal is present in a cationic form, and then reducing to form the free metal, as described for example in Belgian Patent No. 598,686.

Although as indicated above, substantially any hydrocracking catalyst may be used herein, it is not to be assumed that all such catalysts are equivalent, or that they will all give a commercially feasible process. For hydrocracking at below about 825° F. as required herein, and in the presence of ammonia, it is highly desirable to use catalysts which have both a high cracking activity and high hydrogenating activity; otherwise it will be necessary to employ uneconomical low space velocities. For economical processes operated at above about 0.5 LHSV, the preferred catalysts are composed of a Group VIII noble metal, e.g., platinum, palladium, rhodium, iridium or ruthenium, combined by ion exchange with one of the zeolitic molecular sieve cracking bases of the Y crystal type, wherein the zeolitic cations are predominantly hydrogen and/or a divalent metal such as calcium, magnesium, or zinc. The more conventional catalysts such as platinum on silica-alumina gel, or nickel on silica-alumina gel, will require low space velocities, in general below about 0.5 in order to achieve the desired conversion at the specified hydrocracking temperatures.

The following example is cited to illustrate the invention, but is not to be construed as limiting in scope:

Example

This example demonstrates the superior activity of a hydrocracking catalyst preheated to hydrocracking temperatures with a hydrofiner effluent derived from the hydrofining of a substantially nitrogen-free startup feed to which ammonia had been added in the form of t-butylamine. The startup feedstock was a light gas oil 5 boiling between about 420° and 520° F., containing about 2.6 parts per million of nitrogen, 12 parts per million sulfur, and 24 volume-percent aromatics. The high-nitrogen process feed was a heavy coker distillate gas oil boiling over the range of about 400-875° F., having an API gravity of 24.6°, and containing 0.237 weight-percent nitrogen and 0.77 weight-percent sulfur. The hydrofining catalyst was a presulfided composite of about 10 3% cobalt oxide and 15% molybdenum oxide supported on an alumina carrier which was stabilized by the addition of 5% SiO_2 . The hydrocracking catalyst was composed of about 0.5% by weight of palladium added by ion exchange to a mixed magnesium-hydrogen zeolite of the Y crystal type, containing about 3 weight-percent MgO . (35% of total zeolitic exchange capacity), and having a 15 silica/alumina mole-ratio of about 4.7. Conditions which were substantially constant throughout the startup in both the hydrofining and the hydrocracking reactor, were: Pressure 1,500 p.s.i.g., hydrogen-to-oil ratios about 6,000-8,000 s.c.f./b. of feed. Liquid hourly space velocities 20 were about 0.8 in the hydrofiner and 1.5 in the hydrocracker.

The hydrocracking catalyst was first brought up to about 400° F. during an activation cycle with circulating hydrogen, and was then preheated to about 650° F. by circulating the hot hydrofiner effluent therethrough, containing 0.5 weight-percent nitrogen as ammonia during the first 16 hours and 0.2 weight-percent during the last 6 hours, after which the flow of startup feed was terminated, and 100% process feed was used. To reach the desired conversion per pass of 40% by volume to 400° F. end-point gasoline, it was found that an initial temperature of about 705° F. was required, which increased after 25 12 days of operation to about 711° F.

In an analogous startup procedure as described in Example I of Serial No. 265,648, wherein the hydrocracking catalyst was preheated with a hydrofiner effluent derived from the hydrofining of various blends of nitrogen-containing process feed and nitrogen-free startup feed, the initial hydrocracking temperature required for 40% conversion was 713° F., which increased to about 719° F. after 10 days onstream. Thus, the startup procedure of this invention yields a catalyst having about a 7-8° F. 30 temperature advantage over the catalyst placed onstream by the startup procedure described in Serial No. 265,648.

Results analogous to those described in the foregoing example are obtained when other feedstocks, other catalysts and other hydrocracking conditions within the purview of the broad disclosure are substituted in the said example. It is not intended that the invention should be limited to the details described herein, since many 35 variations may be made by those skilled in the art without departing from the scope or spirit of the following claims.

We claim:

1. In an integral catalytic hydrofining-hydrocracking 40 system wherein a hydrocarbon process feedstock contaminated with organic nitrogen compounds is hydrofined with added hydrogen over a bed of hydrofining catalyst at temperatures between about 650° and 850° F., and wherein the total effluent from said hydrofining is 45 then hydrocracked over a bed of hydrocracking catalyst at temperatures between about 650° and 850° F., the improved method for establishing said system and raising the temperature of said catalyst beds from initial temperatures below about 500° F. to the desired hydro- 50

fining and hydrocracking temperatures without damaging said hydrocracking catalyst, which comprises:

- (1) establishing a startup contacting sequence wherein a feed mixture of hydrogen and a relatively pure hydrocarbon startup feedstock substantially free from organic nitrogen is preheated and passed through said hydrofining catalyst bed and then through said hydrocracking catalyst bed while maintaining added ammonia in the feed mixture to said hydrocracking catalyst bed;
  - (2) continuing said startup contacting sequence while incrementally raising the hydrofining inlet temperature of said feed mixture, thereby gradually raising the bed temperature of said hydrofining catalyst to the desired initial hydrofining temperature for said hydrocarbon process feedstock, and also gradually raising the bed temperature of said hydrocracking catalyst to the desired initial hydrocracking temperature, between 650° and 775° F.; and then
  - (3) substantially immediately thereafter, establishing and maintaining the desired process feed contacting sequence by substituting said process feedstock for said startup feedstock and simultaneously terminating said addition of ammonia.
2. A process as defined in claim 1 wherein said added ammonia is added to the feed mixture to said hydrofining catalyst bed.
3. A process as defined in claim 1 wherein said added ammonia is added to the effluent from said hydrofining catalyst bed.
4. A process as defined in claim 1 wherein said hydrocracking catalyst comprises a minor proportion of a Group VIII noble metal hydrogenating component combined with a crystalline, zeolitic molecular sieve of the Y crystal type wherein the zeolitic cations are selected mainly from the class consisting of hydrogen and divalent metals.
5. A process as defined in claim 1 wherein said startup contacting sequence and said process feed contacting sequence are carried out at pressures between about 500 and 2,500 p.s.i.g.
6. In an integral catalytic hydrofining-hydrocracking system wherein a mineral oil process feedstock containing at least about 50 p.p.m. of organic nitrogen is hydrofined with added hydrogen over a bed of hydrofining catalyst at temperatures between about 650° and 850° F., and wherein the total effluent from said hydrofining is then hydrocracked over a bed of hydrocracking catalyst at temperatures between about 650° and 850° F., the improved method for establishing said system and raising the temperature of said catalyst beds from initial temperatures below about 500° F. to the desired hydrofining and hydrocracking temperatures without damaging said hydrocracking catalyst, which comprises:
- (1) establishing a startup contacting sequence wherein a feed mixture of hydrogen and a relatively pure hydrocarbon startup feedstock substantially free from organic nitrogen is preheated and passed through said hydrofining catalyst bed and then through said hydrocracking catalyst bed while maintaining added ammonia in the feed mixture to said hydrocracking catalyst bed;
  - (2) continuing said startup contacting sequence while incrementally raising the hydrofining inlet temperature of said feed mixture, thereby gradually raising the bed temperature of said hydrofining catalyst to the desired initial hydrofining temperature for said process feedstock, and also gradually raising the bed temperature of said hydrocracking catalyst to the desired initial hydrocracking temperature, between about 650° and 775° F.;
  - (3) controlling the rate at which the temperature of said hydrocracking catalyst bed is raised in step (2) so as to maintain bed temperatures below about 500° F. until after said hydrocracking catalyst bed

is substantially saturated with adsorbed ammonia as indicated by the appearance of ammonia in the effluent therefrom;

(4) substantially immediately upon reaching hydro-cracking temperatures as recited in step (2), establishing an interim contacting sequence wherein the flow of said startup feedstock is incrementally reduced and replaced incrementally with said process feedstock while terminating the addition of ammonia and

(5) establishing and maintaining the desired process feed contacting sequence by terminating the flow of said startup feed and continuing the flow of process feed in the absence of added ammonia.

7. A process as defined in claim 6 wherein said added ammonia is added to the feed mixture to said hydrofining catalyst bed.

8. A process as defined in claim 6 wherein said added

ammonia is added to the effluent from said hydrofining catalyst bed.

9. A process as defined in claim 6 wherein said hydrocracking catalyst comprises a minor proportion of a Group VIII noble metal hydrogenating component combined with a crystalline, zeolitic molecular sieve of the Y crystal type wherein the zeolitic cations are selected mainly from the class consisting of hydrogen and divalent metals.
